UNITED STATES PATENT OFFICE.

ALBERT HOYT TAYLOR, OF WASHINGTON, DISTRICT OF COLUMBIA, ASSIGNOR TO WIRED RADIO, INC., OF NEW YORK, N. Y., A CORPORATION OF DELAWARE.

RADIO RECEIVING CIRCUIT.

Application filed July 2, 1920. Serial No. 393,570.

My invention relates generally to directional radio receiving circuits and has for an object thereof to produce a substantially perfect blind spot or direction of no signals.

Another object of my invention is to provide means whereby the blind spot may be rotated (in a horizontal plane) with respect to the vertical plane of the antenna.

10 Another object of my invention is to eliminate residual directional discrepancy in the linear collectors or antenna wires.

Still another object of the invention is to provide means whereby asymmetrical 15 capacities in the receiving set may be neutralized.

A further object of my invention is to provide a circuit of this character by which it is possible to receive signals through an 20 exceedingly strong local interference.

A still further object of the invention is to provide means by which it is possible to select the station from which it is desired to receive and practically eliminate other 25 stations that may be transmitting at the same time and on the same wave length; and also to make such selectivity possible even in the presence of strong local interference.

The invention will now be described in 30 detail, reference being had to the accompanying drawings in which:

Figure 1 is a diagrammatic view of the complete circuit, and

Figures 2 to 8 inclusive are diagrams assisting in the explanation of the theory of the circuit.

With reference to Figure 1, letters A, A, indicate two ordinary linear ground wire collectors or other forms of low horizontal antennæ. The two collectors form a straight line approximately at right angles to the direction from which maximum interference is to be expected.

The collectors are connected to the primary L^1 of the receiver in the usual manner, with the exception that there is a variable resistance R, R , inserted in series with each wire, by which the intensity of the received signal may be varied.

50 The secondary of the receiver is of the usual type and is indicated by reference character L^2 .

Connected across the primary L^1 of the receiver is a resistance R^1 , and traveling over 55 the same is a slider B. Connected with

the slider is an auxiliary adjusting circuit consisting of a variable condenser C and inductance coil L^3 joined in series with ground G or its equivalent, a counterpoise. It is well known that to obtain the best results with linear collectors the wires should be of a certain length, varying with the wave length received, but as it is not possible in actual practice to vary the length of the wire for a wide range of wave lengths, I accomplish the desired result by the introduction of resistances R, R. As previously stated the resistances R, R also serve to vary the intensity of the received signal. Obviously, resistances R, R, could be omitted where the collectors are of the optimum length for the wave length used. The resistance of R^1 need not be great as I have found 80 ohms suitable in practice.

I will now give the theory of the action of my circuit, which theory will clearly show how a substantially perfect blind spot may be obtained, how this blind spot may be rotated, and also how asymmetrical capacities in the receiving set may be neutralized.

First, directivity of a pair of linear collectors in substantially a straight line, one of which is connected to one primary binding post and the other to the other primary binding post of a receiver, is essentially the figure 8-shaped directivity as shown in Figure 2. This directivity is substantially the same as that of the loop and, just as in the case of the loop, it is found in actual practice that the minimum is not absolute, but is disturbed by a residual effect which, in the case of the loop, is known as the antenna effect and should probably go by the same name in the case of the pair of linear collectors. The receiving set itself having a certain capacity to earth, which may not be symmetrically distributed, introduces this antenna effect which results in a slight blurring of the minimum as shown by the shaded areas in Figure 2. One of the purposes of the invention herein discussed is to bring about an absolutely sharp minimum in order to completely exclude powerful interferences from directions not coinciding with the direction of the signal. With reference to Figure 1, it may be stated that the shunting of the moderately high resistance across the primary does not materially change the directivity of the system but offers an adjustable means of accentuating the antenna

105 110

effect in either right or left linear collector. Figure 3 shows the nature of the directivity which may be expected when a linear collector of no great length is used connected to one terminal of the receiving set and a ground connection to the other terminal and on the assumption that the antenna effect is approximately equal to the horizontal linear collector effect and that by some means their phases are properly adjusted. This type of directivity corresponds to that which is obtained with the herein discussed invention when the slider "B" is moved to the left hand end of the resistance R' .

This type of directivity may be called cardiac and is due to the compounding of a circular directivity as shown in Figure 4, which is typical of an ordinary antenna, with the figure 8 directivity which is typical of horizontal linear collectors and loops. There does not appear to be an antenna in the system herein described, nevertheless, such antenna is actually present. It must be remembered that any linear collector will, in practice, be used either a few feet above the ground, on the ground, or a few feet under the ground, and that in all these cases, even the last one, its actual level is above the center of gravity of the permanent ground (that is, permanent conducting sheet of the earth's surface). Figure 5 shows the general nature of the electric vector in a wave traveling over the surface of the ground. On account of the inclination of this vector, it will be seen that it has a weak horizontal component but a strong vertical component. The vertical component is ordinarily used in antenna reception, whereas the horizontal component comes into play in the use of linear collectors placed substantially horizontal. For this reason it is always necessary to use considerable amplification when receiving from horizontal collectors, or nearly horizontal collectors, when the same are of moderate length. On account of the slight inclination of the wave front, it will be seen by reference to Figure 5 that a horizontal collector several hundred feet in length is able to develop no more electromotive force from the reception of the weak horizontal component of the electric vector than is a vertical antenna of only a few feet in height receiving the strong vertical component. If, therefore, a linear collector, for instance 200 feet long, be only two feet above the permanent ground (center of gravity of ground conducting sheet) the antenna effect, which is not directional, will be of the same order of magnitude as the linear collector effect which is directional. Although the components of the electric vector are naturally in phase, the resulting horizontal and vertical components of electromotive force do not necessarily produce currents in phase with each other, as this will depend upon the way

the circuit is permitted to respond to these two electromotive forces. Figure 6 shows the result of combining a circular directivity with a figure 8 directivity, the circular directivity being the antenna effect and the figure 8 being the linear collector or loop effect, the intensities not being quite equal. The cardiac directivity figure is the result. This then is the type of directivity we may normally expect from a linear collector which is connected to one post of the receiver, the other post being connected to the ground, except in such cases where the linear collector is very long in comparison to its height above the center of gravity of ground. Such a case is actually observed in long wave reception with wires from 1,500 to 2,000 feet in length. There has been in the past considerable dispute as to whether such a wire received stations better from the direction in which the ungrounded end of the wire points or vice versa. The theory shows that it all depends upon the horizontal length of the linear collector used and its height above the location of the center of gravity of permanent ground. Actually, there is probably always some difference, the antenna effect acting to blur the minimum of the figure 8 or normal linear collector type of directivity and to give a slight tendency towards a cardiac form.

The invention herein described refers to a case where by the use of high amplification it is possible to utilize relatively short linear collectors and where, therefore, the antenna effect in said collectors is of the same order of magnitude as regular bi-directional or linear collector (similar to loop) effect. Longer wires might be used if the antenna effect is intentionally accentuated either by lifting the linear collectors or by attaching to them a vertical section (antenna) of the proper dimensions.

With reference to Figure 1, when the slider B is pushed completely to the left, the primary circuit is traversed by two currents, one of which passes from the right hand linear collector to the left hand linear collector and which corresponds to the figure 8 directivity, and the other which passes from the right hand linear collector through the primary of the receiver and thence thru the auxiliary adjusting circuits tuned by the condenser "C" and inductance following it, to a counterpoise or ground connection. This second current is due to the difference of potential between the linear collector and ground, and its phase is adjustable by the condenser "C" independently of the phase adjustment of the other current component. It is thus seen that all the elements are present which are necessary to get a combination of circular directivity and figure 8 shaped directivity, which combination is the cardiac directivity. The circulation of cur-

rents in this case is such as to make the circuit blind to the right. (See Figure 3). The left hand linear collector discharges its component of current due to antenna effect directly through the tuned adjusting circuit to counterpoise or ground, only a small portion of it passing back through the primary to the other linear collector and thus by capacity effect to ground. Nevertheless, this small portion may be objectionable for signals from certain directions and for powerful local interferences. A certain amount of regulation is obtained by the use of the resistance R in series with the linear collectors. If the slider "B" is now moved to the opposite end, namely to the right, the left hand linear collector discharges its antenna effect through the primary and since the phase of the current due to the other effect, i. e., regular linear collector figure 8 shaped directivity, is opposite to what it is for the right hand linear collector, it is evident that the cardiac figure of resultant directivity will be reversed as shown in Figure 7. If the slider "B" is placed in the center, both linear collectors get rid of the antenna effect currents equally and symmetrically through the tuned by-pass and, as far as the primary is concerned, mutually oppose each other so as to cancel except in so far as there may be, as outlined above, unsymmetrically distributed capacities in the receiving set. By deviating the slider "B" slightly one way or the other from the center, sufficient asymmetry in the antenna effect currents may be arbitrarily produced so as to accurately offset asymmetrical capacities in the receiving set, thus making the minimum exceedingly sharp. If then the slider "B" be started at the left, the circuit receives strongly from the left; it also receives very well from directions at right angles to the linear collector system and on either side of it, but it is nearly blind to signals coming from the right. This type of directivity, as the slider is moved, changes slowly over until when the slider is near the middle, the directivity is sharply figure 8, receiving equally well from right and left but nothing at right angles. If the motion is then continued the cardiac figure appears again, reversed from its original position and the circuit receives best from the right, fairly well from directions at right angles to the linear collector system, but has a blind spot to the left. It is evident that between the extreme positions and the middle that all kinds of intermediate types of directivity may be obtained. The action is probably somewhat more complicated than herein described, but in actual practice it is seen that the blind spot will wander around from one point of the compass to another 180 degrees distant by simply moving the slider and adjusting the

tuning condenser "C" in the counterpoise or ground circuit. In other words, the circuit may be made absolutely blind in practice over a very considerable angle, in fact, nearly blind completely around the compass. In practice it is evidently possible to produce not only cardiac directivity with right and left hand blind spots, or nearly blind spots, but that blind spots may be produced in other directions than parallel and at right angles to the system. This is similar to what happens when an antenna is loosely coupled to a loop, said antenna producing a weaker signal than the loop. This case is shown in Figure 8 and gives a figure differing only slightly from the cardiac shown previously and containing two blind spots, neither of which is opposite to the direction of maximum reception. It is evident that two loops can be used with this circuit, provided that their dimensions are such that they simulate the relative amount of antenna effect and bi-directional effect of the linear collectors. Such loops will be relatively tall and narrow and with a small number of turns. The argument of the theory is essentially the same when applied to loops and will not be herein repeated.

From the above description it is clear that I am able, by means of the auxiliary adjusting circuit, to produce a substantially perfect blind spot at right angles to the direction of the linear collectors; when the slider B is near the center of the resistance R' ; that by placing the slider near either of its extreme positions the circuit may be made blind to either the right or the left; and that for intermediate positions of the slider the blind spot will be rotated to intermediate positions. It follows therefore that if several stations at different points of the compass are transmitting at the same time and on the same wave length, then by means of the above described adjustments it is possible to favor the station it is desired to copy and to substantially eliminate the others; and further, this result may be accomplished through a strong local interference.

Another feature of my invention is the elimination of residual directional discrepancy. It is impossible in practice to lay the linear collectors at absolute right angles to the direction of maximum interference, and it also is impossible to have the wires in a perfectly straight line. There results, of course, an imperfect blind spot. The flexibility of directivity obtained by the use of my auxiliary adjusting circuit, permits the equivalent of a slight rotation of the collectors whereby any residual directional discrepancy is eliminated.

While I have shown and described my invention as applied to linear collectors in underground systems, this is not to be con-

sidered in a limiting sense as the circuit is
equally well adaptable to use in connection
with either loops or linear collectors located
underground, under water, on the ground
or above the ground.

Having thus described my invention what
I claim and desire to secure by Letters Patent
of the United States is:

1. A directional antenna and means associated
therewith for producing a substantially
perfect blind spot comprising an auxil-

iary circuit associated with said antenna
and a resistance with variable contact connecting
said antenna and auxiliary circuit.

2. A directional antenna and adjusting means
associated therewith for neutralizing
asymmetrical capacities in the receiving set
comprising an auxiliary circuit associated
with said antenna, and a resistance with variable
contact connecting said antenna and auxiliary circuit.

ALBERT HOYT TAYLOR.
